AUTOMATIC SCREW-CUTTING LATHE

Ernest Bodmer, Grand-Lancy-Geneva, Switzerland, assignor to Tarex S. A., Geneva, Switzerland, a corporation of Switzerland

Application April 8, 1946, Serial No. 660,503
In Switzerland June 6, 1945

2 Claims. (Cl. 10—105)

1

Automatic screw cutting lathes most appreciated at the present time are provided with a device for controlling the movement of the crossed slides of the tool holder having a lead screw, driven in rotation, cooperating with a nut sliding parallel to the axis of the lead screw and capable of oscillating in a plane perpendicular to this axis. Cams produce at the beginning and end of the working stroke the engagement and disengagement respectively of the nut with the lead screw. The movements of the nut, parallel to the axis of the lead screw, control the movements of the longitudinal slide of the tool holder. These lathes have certain disadvantages due to the fact that the nut must be capable of carrying out movements in two planes perpendicular to one another on the one hand, and on the other hand due to the fact that the disengagement of the nut from the lead screw at the end of the working stroke is produced by a cam. In fact in order to enable the nut to carry out movements in two planes perpendicular to one another, manufacturers have in general secured the nut to a sleeve mounted on a rod capable of sliding in its bearings. It will be obvious that such a mounting is difficult to realise as when a great precision of screw cutting is required, the clearances must be reduced to a minimum. Further the sleeve has in general a collar adjustable in longitudinal position. The collar is provided with a nose adapted to cooperate with the cams at the beginning and end of the working stroke of the tool. But it is clear that the bearing length which the said nose can present to the cam which acts thereon is at the maximum equal to the pitch of the thread of the lead screw. The nose and the cam thus wear rapidly and the control of the release of the nut is liable to be effected a revolution too late. Consequently the tool is liable to bite into the material and either be broken or in any case heated to such a temperature that its resharpening is necessary. But after each resharpening the whole adjustment of the lathe must be effected afresh and controlled if it is desired to obtain a precision screw thread. Further according to the degree of wear of the nose cooperating with the cam, it is possible that the nut remains half engaged with the lead screw. In this case there occurs a local rapid wear of the lead screw and nut.

From the foregoing it will be seen that the lead screws and the nut of known automatic screw lathes wear relatively rapidly and particularly nonuniformly so that it is necessary to test them frequently.

For the purpose of eliminating some of the disadvantages referred to, some manufacturers have

2

hinged the nut holder directly on the longitudinal slide of the tool holder carriage. Such a construction, however, is not desirable as it increases the weight of the tool holder carriage of the lathe.

5 But in view of the high cutting speeds possible at the present time by reason of the special steels placed on the market, the return of the slide to the starting position should be more rapid as it should be effected in a period of time considerably shorter than the duration of a complete revolution of the cam shaft controlling the engaging and disengaging movements of the nut, and that this cam shaft cannot be driven at a speed much less than that of the lead screw, or 10 else the engagement and disengagement of the nut is not effected in a precise manner.

The present invention has for its subject a device for controlling the movements of the longitudinal slide of the tool holder of a screw cutting lathe, which tends to eliminate the disadvantages referred to. This device is provided with a lead screw cooperating with a nut and is distinguished from known devices by the fact that the lead screw is movable axially and is connected by connecting members to the longitudinal slide of the tool holder and by the fact that the nut, movable in a plane perpendicular to the axis of rotation of the lead screw, is held against any movement parallel to the said axis.

20 30 One form of construction of the subject of the invention is shown diagrammatically and by way of example in the accompanying drawing.

In the drawing only the members necessary for the understanding of the devices for controlling the longitudinal slide have been shown.

35 The spindle 1 of the screw cutting lathe, pivoted in bearings 2, is driven by a motor M. The part 4 to be screw threaded is held clamped in the spindle by one of its ends whilst its other end is held in position by a back centre 5.

The lathe is provided with a tool holder carriage with crossed slides, of which the transverse slide 6 is guided by guides provided in the framework 3 and carries the longitudinal slide 7 guided by guides, provided in the transverse slide 6. The longitudinal slide 7 is subjected to the action of a return spring 8 tending to hold it in engagement with a rest stop 9 adjustable in position.

40 50 The longitudinal slide 7 is connected by transmission members to a lead screw or "master" 10. The latter is driven in rotation by the motor M and by means of an interchangeable gear train. The lead screw is mounted rigidly on a shaft 11 55 of which one end 12 is grooved and slides inside a sleeve 13. This sleeve rotates in a bearing 14 provided in the framework of the lathe and car-

ries two gears 15, 16 each secured rigidly to one of its ends. The gear 15 gears with a toothed wheel 17 secured to the shaft of the spindle 1. The shaft 11 is thus driven in rotation by the motor M, further it is connected by means of a coupling 18 to a pusher 19 sliding in a guide 20 provided in the framework of the lathe. A finger 21, engaging with a groove 22, prevents any angular movement of the pusher. At its free end the pusher carries a finger 23 engaging with a transverse groove 24 of the slide 7. The nut 25 slides in a seating 26 provided in the framework. An actuating finger 27 engaging with a seating 28 controls the movements of the nut producing its engagement with and its disengagement from the lead screw 10. The finger 27 is mounted rigidly on a shaft 29 turning in bearings provided in the framework of the lathe. The shaft 29 also carries a lever 30 of which the free end cooperates with a cam 31 producing the engaging movements of the nut at each return of the carriage to the normal position. The cam 31 is secured to a shaft 32 driven in rotation by the motor M and by means of gears 17, 15, 16, 33, 34 and a clutch 35. The disengagement of the nut, on the contrary, is produced by a quick action relay set in operation at the end of each working stroke of the tool. This relay is formed by a spring 100 mounted on a rod 101 sliding in seatings provided in the framework and carrying a rack 102 and a pusher 103.

The rack 102 engages with a toothed sector 104 mounted rigidly on a shaft 105 and provided with an arm 106 of which the end cooperates with a finger 107. The latter is mounted on a shaft 108 of which the angular movements are controlled, against the action of a return spring 109, by the movements of the longitudinal slide 7.

A second toothed sector 110, secured to the shaft 105, engages with a toothed sector 111 secured to the shaft 29 and thus connects the rod 101 mechanically to the finger 27 which controls the movements of the nut.

The pusher 103 is connected by a train of transmission members:

1. To a crank pin 60 for controlling the advance of the tool in depth between each cut,

2. To an oscillating finger 61 engaging with a groove 62 of the rule 41 and controlling the movements of this and thus the withdrawal and engagement of the tool with the workpiece which is being machined at the end and beginning of each cut.

The engaging and disengaging movements of the driving and driven parts of the clutch 35 are controlled manually. For this purpose one of the parts of the clutch 35 is connected by means of transmission members to an operating member L. The latter is also connected, by a train of transmission members comprising a shaft 112 rigid with handle L and gear 113 meshing with gear 114 on shaft 115, to a sleeve 36 fixed to shaft 115 carrying a toothed sector 37 engaging with a rack 38 sliding in a guide 39 provided in the transverse slide 6. The end 40 of this rack cooperates with the lateral face of a rule 41 sliding in a guide 42 of the slide 6. The guide 42 is arranged in a plane perpendicular to the plane of the guide 39 and a spring 43 tends to hold the lateral face of the rule in contact with the end 40 of the rack. The operation of the member L thus produces simultaneously:

1. The engagement of the driven and driving parts of the clutch 35,

2. The setting in the transverse position at the

start of operation of the tool holder carriage by the movement of the transverse slide 6 against the action of its return spring 43 which tends to hold it in the position of rest, that is to say in engagement with a rest stop 44 adjustable in position.

The angular movements of the sector 37 producing the feed in depth of the tool between each cut are controlled by a device described in a co-pending application of the same date.

The operation of the device for controlling the movements of the longitudinal slide is as follows:

The motor M being under voltage, the setting in operation of the device is obtained by the operation of the manual member L, in a clockwise direction, so as to bring it up to the position shown in the drawing. This operation produces the engagement of the driving and driven parts of the clutch 35 on the one hand, and on the other hand the actuation of the transverse slide 6 from its position of rest, against the action of its return spring, up to the advanced position (position shown) in which the tool is not yet in engagement with the part 4.

When the clutch 35 is in the engaged position the shaft 32 sets in rotation the cam 31 which produces an angular movement of the arm 30, the end of which rests on its profile. This angular movement of the arm 30 produces:

1. The swinging of the finger 27 and the engagement of the nut 25 with the threads of the lead screw 10,

2. By means of the toothed sectors 111, 110, 104 and the rack 102, the movement, towards the right of the drawing, of the rod 101 and the compression of the spring 100.

3. The angular movement of the arm 106 up to the position shown in the drawing, for which the finger 107, cooperating with the end of the said arm prevents any movement of the rod 101 under the action of the spring 100,

4. By means of the pusher 103, the movement of the rule towards the left of the drawing and the transverse feed of the slide 6 bringing the point of the tool flush with the surface of the part to be machined,

5. By means of the pusher 103, the rotation in a clockwise direction, of the actuating crank pin for the feed in depth. This angular movement of the crank pin 60 produces by means described in the copending application the feed in depth of the tool.

As the lead screw is rotating and the nut engaged, this is subjected to an axial movement towards the right of the drawing. During its movement it so drives the slide 7 that as the part 4 is being driven in rotation by the motor M, the tool 79 cuts a thread.

At the end of the working stroke, a stop 81 actuates a pusher 82 against the action of the spring 109 and produces the disengagement of the bolt 107, 106 which holds the relay in the set position (position shown).

From now on the relay, formed by the spring 100, is set in action and produces:

1. The sudden and rapid return of the nut,

2. The movement to the right of the drawing of the rule 41 and the recoil of the slide 6 as also the disengagement of the tool from the part which is being machined.

As the nut is disengaged from the lead screw, the spring 8 repels the longitudinal slide 7 up to its position of rest, defined by the stop 9.

As the shaft 32 continues its rotation the cam

31 again actuates the lever 30 and the same cycle of movement is effected a second time.

However in order to prevent the cam 31 from actuating the lever 30 at the moment of opening the bolt 107, 106 which would prevent the withdrawal of the nut, an interlocking device is provided. This device prevents the action of the lever 30 by the cam 31 as long as the bolt 106, 107 is in the position shown in the drawing, that is to say in the closed position. This device is formed by a bolt 83, 84 held in the closed position (position shown) by a spring (not shown). The part 83 of the bolt, carried by the lever 88 and pivoted at 85, is actuated, against the action of the return spring, at the end of the return stroke of the longitudinal slide. For this purpose the pusher 19 carries a driving finger 86 adapted to cooperate with a pin 87 secured to the lever 88. The cam 31 slides on the shaft 32 and a spring 89 tends to hold it out of range of the lever 30 so that it cannot produce the oscillation of said lever. The second part 84 of the bolt is formed by an arm secured to a sleeve 90 mounted loosely on the shaft 29. This sleeve carries a second arm 91 carrying a pin 92 adapted to cooperate with a ramp 93 secured to the cam 31.

When the bolt 83, 84 is open, the arm 91 oscillates and the pin 92 cooperating with the ramp 93 moves the cam 31, against the action of its spring 89, through an amount sufficient to cause it to cooperate with the lever 30. Thus it is only when the longitudinal slide is in the position of starting the machining that the cam 31 can produce:

1. The engagement of the nut with the lead screw,
2. The resetting of the relay formed by the spring 100,
3. The feed in depth of the tool,
4. The setting in the operative position of the tool by actuating the rule 41.

Thus the security in operation is complete and no error of control can be produced irrespective of the speed of rotation of the spindle.

During each working stroke the tool cuts the thread deeper in the part 4.

From the foregoing it will be seen that the longitudinal slide must necessarily effect the same movements as the lead screw, which ensures the precision of the pitch of, the screw thread on the part 4, clearances being capable of being reduced easily to a minimum and on the other hand as the thrusts always act in the same direction, these clearances are practically eliminated. Further the disengagement of the nut is controlled by a quick action relay set in operation by the movements of the longitudinal slide in such a manner that this disengagement is always controlled with precision at desired moments on the one hand, and is effectuated on the other hand by a sudden and rapid movement of the nut 25 under the action of the relay, whereby there is avoided as far as possible wear of the nut and local wear of the lead screw.

Further the entire device for controlling the movements of the crossed slides of the tool holder carriage may be secured on the framework of the lathe in such a manner that the carriage is relieved of the whole of the weight of these latter. This results in greater stability of this movable part and thus in greater precision in machining. The inertia of the parts in movement being less, the wear of the lathe is reduced correspondingly.

A form of construction of the device for controlling the movements of the longitudinal slide 75

of a tool holder of a screw cutting lathe has been described with reference to the accompanying drawing. However it is clear that this device may be applied to the control of the longitudinal slide of tool holders of different conception for example with a lower longitudinal slide and an upper transverse slide.

Further the control of the disengagement of the nut may also be effected, in the same way as in known devices, by a second cam mounted on the shaft 32. Finally the nut may be pivoted at its free end on a shaft parallel to the axis of the lead screw. Angular movements—in a plane perpendicular to the axis of the lead screw—may then be controlled directly by cams mounted on the shaft 32.

I claim:

1. In a screw cutting lathe, the combination, comprising, a frame, a slide mounted for movement longitudinally of the frame, a lead screw connected to the slide and mounted in said frame for rotation and axial movement, a motor rotating said screw, a lead nut held by said frame against movement parallel to said screw and engageable with same to move same axially during rotation, spring means for holding said nut out of engagement with said screw, means holding said nut in engagement with said screw against the action of said spring means, and a locking device preventing stressing of said spring means and the engagement of said nut with said screw as long as said longitudinal slide is out of its position at the starting end of the work stroke.

2. In an automatic screw cutting lathe, the combination of a frame, a slide mounted for movement longitudinally of the frame, a lead screw connected to said slide and mounted in said frame for rotation and axial movement, a motor rotating said screw, a lead nut held by said frame against movement parallel to said screw and engageable with same to move same axially during rotation, spring urged means normally holding said nut from engagement with the screw, means operable by the motor and holding said nut in engagement with said screw and connected to said spring urged means and during its operation stressing the spring thereof, and a locking device preventing the operation of the spring stressing means and the engagement of said nut with said screw as long as said longitudinal slide is out of its position at the starting of the work stroke, said locking device being releasable by the lead screw and rendering the nut holding means inoperative.

ERNEST BODMER.
